UNITED STATES PATENT OFFICE.

WILLIAM C. TREGONING, OF HACKENSACK, NEW JERSEY, ASSIGNOR TO THE TREGONING ELECTRIC MANUFACTURING COMPANY, OF CLEVELAND, OHIO, A CORPORATION OF OHIO.

TERMINAL-CONNECTOR.

No. 909,481.

Specification of Letters Patent.

Patented Jan. 12, 1909.

Application filed October 22, 1906. Serial No. 339,941.

To all whom it may concern:

Be it known that I, WILLIAM C. TREGONING, a citizen of the United States, residing at Hackensack, New Jersey, have invented 5 certain new and useful Improvements in Terminal-Connectors, of which the following is a clear, full, and exact description.

The object of this invention is to provide an improved connector terminal for making 10 battery or other electrical connections, which will be simple and cheap to make, readily applied and will of itself secure a good electrical connection.

In carrying out the invention I provide 15 members resiliently movable away from each other at their outer ends and joined at their inner ends. I provide a means which normally tends to hold the outer ends apart, which I prefer to have consist of the spring 20 quality of the material of which the terminal is made. The terminal is usually formed of wire, in which case the spring is secured by a convolution of the wire itself. The conductor may be secured to either member of 25 the terminal connector in any desired manner, as by winding or soldering.

At the free ends of the members I locate 30 loops so situated that they are in the same plane of movement as the members themselves, so that when the members are compressed the loops may overlie each other and be slipped over the terminal post or screw, that is to receive them. When so slipped over a post or terminal and released, the 35 spring of the connector will tend to separate the two members and thus cause each of them to strongly grip opposite sides of the terminal.

When the loops are formed of sheet metal, 40 I prefer to corrugate or screw thread them that they may take hold of a shank of a terminal screw of ordinary style, in which case I also prefer to have the loops of sufficient depth to form sleeves or cylinders so as to get 45 a better surface contact. When made of wire the loops, instead of being of but one convolution, may be of a number with the successive loops closed on each other, in which case the spiral itself will in good manner partake of the shape of the threaded 50 terminal.

In the accompanying drawings, Figure 1 is 55 a plan view of my improved terminal connector showing the preferred form; Fig. 2 is a side elevation of Fig. 1; Fig. 3 is a plan view

of the terminal connector of Figs. 1 and 2 with the loops closed upon each other for insertion on a post; Fig. 4 is a plan view of a modified connector in closed position; Fig. 5 is a side elevation of the terminal of Fig. 4; Fig. 6 is a 60 plan of a still further modification, and Fig. 7 is a side elevation of Fig. 6 with one of the sleeves in section.

As shown in Figs. 1, 2 and 3, the terminal connector consists of one piece of wire having 65 two straight members 1, 1, each terminating in a sleeve 2 of closed loops of the wire, each loop being oppositely turned so that a continuous sleeve with a substantially threaded interior will be provided with the threads, 70 preferably all running one way.

The two members 1 are joined at their inner end by a spring loop 3 which tends always to open them out into the position of Fig. 1. The conductor 4 may be passed 75 through the spring loop 3 and wound or soldered on one of the members as shown.

In the construction of Figs. 4 and 5, the terminal connector is shown as formed of two sheet metal spring members 11. The members have sleeves 12 at their outer ends and each member is of half the entire width of the blank from which it is formed, while the hinge 14 is of the entire width of such blank. The object of this will at once be obvious by 85 reference to Fig. 5 where the parts are shown in position on a threaded post or screw. A hole 15 in the hinge 14 and a smaller opening 16 may be provided for the conductor.

As shown in Figs. 6 and 7 the two mem- 90 bers 21 and 21 and the spring loop 23 are similar to my preferred form, but the sleeves or loops 22, 22 are sheet metal stampings with threaded interiors and with tubular edges 24 to grasp the members 21, 21. It is 95 obvious that these threaded sleeves of sheet metal are just as serviceable with the construction of Figs. 4 and 5 as with that just described.

Though I have shown two different species 100 of terminal construction herein and presented claims generic to both species and others specific to the coiled wire construction, I do not abandon my right to specific claims in another application and patent for that spe- 105 cies unclaimed specifically in this case.

What I claim is:

1. A terminal connector comprising two members joined together and resiliently movable away from each other in planes substan- 110

- 2 tially parallel, the free ends of said members having openings lying in a plane parallel to the plane of movement of said members.
2. A terminal connector comprising two members joined together and each carrying at its free end a sleeve having its axis at right angles to the plane of movement of the members, and resilient means adapted to hold said members away from each other.
- 10 3. A terminal connector comprising two wire members joined with a spiral thereof, the free ends of each member being bent into a loop, having its axis at right angles to the plane of movement of the members.
- 15 4. A terminal connector comprising two wire members joined with a spiral thereof, the free ends of each member being bent into loops of a spiral with the convolutions closed upon each other to form corrugated cylinders.
- 20 5. A terminal connector comprising two wire members joined with a spiral thereof, the free ends of each member being bent into loops of a spiral with the convolutions closed 25 upon each other to form corrugated cylinders, said members being adjacent each other and the cylinders extending oppositely to each other from the outer end.
6. A terminal connector comprising two members joined at one end and resilient means adapted to hold said members away from each other and a cylinder at the free end of each member, having its axis at right angles to the plane of movement of the members.
- 30 7. A terminal connector comprising two members joined at one end and resilient means adapted to hold said members away from each other and a cylinder at the free end of each member, having its axis at right angles to the plane of movement of the members, said sleeve being formed of the body of the metal of which said members are comprised.

Signed at New York city this 20th day of 45
October 1906.

WM. C. TREGONING.
